UNITED STATES PATENT OFFICE.

FRANK LE CLAIR HUTCHINSON, OF WAUWATOSA, WISCONSIN, ASSIGNOR, BY MESNE ASSIGNMENTS, TO MILWAUKEE VALVE COMPANY, OF MILWAUKEE, WISCONSIN, A CORPORATION OF WISCONSIN.

VALVE.

Application filed July 25, 1923. Serial No. 653,694.

To all whom it may concern:

Be it known that I, FRANK LE CLAIR HUTCHINSON, a citizen of the United States, and resident of Wauwatosa, in the county of Milwaukee and State of Wisconsin, have invented new and useful Improvements in Valves, of which the following is a description, reference being had to the accompanying drawings, which are a part of this specification.

This invention relates to valves, and particularly to a valve adapted to be connected to the return pipe in a low pressure vapor or steam heating system.

In heating systems employed in private dwellings where steam under low pressure is employed, it is the present practice to control the admission of steam to the radiator and to provide an outlet pipe to return the water of condensation back to the boiler. In order to make the system conducive of the best results and to provide for its maximum efficiency, it is necessary to prevent the passage of any of the live steam back through the return pipe with the water of condensation. In systems of this character it is also necessary, and is the present practice, to provide means of permitting the escape of air which may be trapped in the radiator, so that this air will not act to prevent the entrance of steam into the radiator.

This invention therefore relates to a valve adapted to be connected to the return pipe, and designed to permit the passage of water therethrough, and also the escape of any trapped air, at the same time preventing the escape of live steam.

The invention furthermore consists in the novel construction, combination and arrangement of parts, all of which will be made more apparent hereinafter as this description proceeds, especially when considered in connection with the accompanying drawings, wherein:

Figure 1 is a longitudinal sectional view, through a valve constructed in accordance with this invention;

Fig. 2 is a detail sectional view of the valve parts removed from the casing;

Fig. 3 is a fragmentary detail elevational view, taken on the plane indicated by the line 3-3 of Fig. 2;

Fig. 4 is an enlarged fragmentary detail

sectional view of the thermostatically controlled valve; and,

Fig. 5 is a detail elevational view of the structure illustrated in Fig. 4.

Referring now more particularly to the drawings it will be noted that the valve consists of a casing 10, provided with an inlet opening 11 and an outlet opening 12. The casing is formed immediately adjacent the inlet opening 11 with a sediment chamber 13 provided with a cleaning opening closed by a plug 14. Communication between the sediment chamber 13 and the float chamber 15 of the valve device is provided by way of an opening 16, formed in the division wall of the valve casing. The upper side of the casing 10 is open and closed by a removable cap 17, preferably threaded therein.

Arranged adjacent the outlet opening 12 is a bushing 18, having formed thereon a valve seat, adapted to receive a valve 19 carried by a hollow tubular valve stem 20. The valve 19 and valve stem 20 are mounted for reciprocal movement in a guide member 21, supported upon a pair of projections 22, extending inwardly from the casing 10. The guide member 21 is perforated centrally thereof for the reception of the valve stem 20.

The guide member 21 is formed with a downwardly extending arm 23, which is pivotally connected as at 24 to an arm 25, connected to a hollow float 26. Fixed to the valve stem 20 is a collar 27, provided with laterally extending trunnions 28, which engage slots 29, formed in the float arms 25. Obviously, therefore, as the float is raised, the valve stem 20 and the valve 19 will consequently be moved upwardly. The compound leverage provided by the arrangement just described, obviously renders the operation of the valve positive under all conditions.

Fixed to the upper end of the tubular valve stem 20 is a collar 30, having fixed thereto a bi-metal thermostat 31, formed preferably of an outer strip of brass or copper and an inner strip of steel or other similar metal, having a different co-efficient of expansion. A valve 32, carried by the end of the thermostat 31 is adapted in its closed position to engage the open end of the valve stem 20, thus closing communication

through this hollow valve stem between the chamber 15 and the outlet 12.

In operation the valve 19 will normally remain in closed position, as illustrated in Fig. 1, while the thermostatic valve 32 remains in open position. Consequently, any air flowing into the chamber 15, through the inlet opening 11, is free to pass from the chamber 15 through the tubular valve stem 10 and downwardly through the outlet opening 12. However, immediately upon the entrance of any steam within the chamber 15, the heat thereof will cause an unequal expansion of the bi-metal parts of the 15 thermostat, and thus effect a closing of the valve 32, so that this live steam will be confined within the radiator.

The water of condensation which flows into the chamber 15 will gradually accumulate until it reaches a height sufficient to actuate the float 26, which, as it rises, will move the valve stem 20 and valve 19 upwardly, thus permitting an escape of this water through the outlet opening 12. As 25 the level of the water decreases, the float will again close and move the valve 19 to its closed position, until the accumulation of a further quantity of the water in the chamber 15.

Obviously, as the water of condensation passes into the chamber 15, any foreign matter contained therein will precipitate into the sediment chamber 18, which can periodically be cleaned out by removing the 35 plug 14. Access to the interior of the valve may be conveniently had by removing the cover 17, and should it become necessary to replace the portion of the operating parts illustrated separately in Fig. 2, this 40 may be accomplished by detaching the guide plate 21 from the projections 22, whereupon all of these parts may be removed as a unit from the interior of the valve. This facilitates, to a considerable degree, the repairing or replacing of parts.

While one specific embodiment of the invention has been described in some detail, it is not intended that the invention be unnecessarily limited, but reservation is made 50 to make such changes as may come within the purview of the accompanying claims.

Having thus described the invention what is claimed is:

1. In a valve of the class described a casting forming a chamber provided with inlet and outlet openings, a float, a valve provided with a stem for controlling said outlet opening, means connecting said float to said stem of said valve having a 55 passage providing communication between said chamber and outlet opening and thermostatic means for closing said passage.

2. In a valve of the class described a valve casing forming a float chamber provided with inlet and outlet openings, a float actuated valve for controlling said outlet opening, said valve being formed with a hollow stem providing a passage between said chamber and outlet opening and a thermostatically actuated valve mounted on the end 65 of said stem for controlling said passage.

3. In a valve of the class described a casting formed with communicating float and sediment chambers and provided with inlet and outlet openings communicating respectively with said sediment and float chambers, a valve provided with a tubular stem for controlling said outlet opening, a float in said float chamber operatively connected to said valve, said tubular stem providing an auxiliary passage connecting said float chamber to said outlet opening and a thermostatically controlled valve mounted on said valve stem for controlling said auxiliary passage.

4. In a valve of the class described, a casting forming a chamber provided with inlet and outlet openings, a float, comprising a closed hollow body, mounted in the chamber, a valve for closing the outlet opening, 90 means for operatively connecting this valve to the float, a tubular stem formed with the outlet valve, to provide an auxiliary passage connecting the chamber with the outlet opening, and means for closing 95 the said auxiliary passage.

5. In a valve of the class described a casting formed with communicating float and sediment chambers, and provided with inlet and outlet openings, communicating respectively with said sediment and float chambers, a valve provided with a tubular stem for controlling said outlet opening, a hollow closed float in said float chamber, operatively connected to said valve, said tubular 100 stem providing an auxiliary passage connecting said float chamber to said outlet opening, and a thermostatically controlled valve mounted on said valve stem for controlling said auxiliary passage.

6. In a valve of the class described a casting forming a chamber provided with inlet and outlet openings, a hollow closed float in the chamber, a valve provided with a tubular stem for controlling said outlet opening, a lever arm pivotally carried by said chamber casing and rigidly secured to the float, operatively connected to the tubular stem of the said valve for controlling the same, and thermostatic means for controlling the passage formed by the tubular 115 stem of the outlet valve.

In testimony whereof, I affix my signature.
FRANK LE CLAIR HUTCHINSON.
